(57) **CLAIM**

The ornamental design for a laryngoscope handle, as shown and described.

DESCRIPTION

FIG. 1 is a perspective view of a laryngoscope handle;

FIG. 2 is a top view thereof;

FIG. 3 is a bottom view thereof;

FIG. 4 is a right-side view thereof;

FIG. 5 is a left-side view thereof;

FIG. 6 is a front view thereof;

FIG. 7 is a rear view thereof.

FIG. 8 is a perspective view of a second embodiment of the laryngoscope handle;

FIG. 9 is a top view thereof;

FIG. 10 is a bottom view thereof;

FIG. 11 is a right-side view thereof;

FIG. 12 is a left-side view thereof;

FIG. 13 is a front view thereof; and,

FIG. 14 is a rear view thereof.

The broken lines in FIGS. 3, 6, 10, and 14 represent unclaimed environment only, and forms no part of the claimed design.
